UNITED STATES PATENT OFFICE.

DAVID HALL RICE, OF BROOKLINE, ASSIGNOR TO C. G. SARGENT'S SONS,
OF GRANITEVILLE, MASSACHUSETTS.

WOOL-WASHING MACHINE.

SPECIFICATION forming part of Letters Patent No. 521,817, dated June 26, 1894.

Application filed April 20, 1892, Serial No. 429,958. (No model.)

To all whom it may concern:

Be it known that I, DAVID HALL RICE, of Brookline, in the county of Norfolk and State of Massachusetts, have invented a new and useful Improvement in Fiber-Washing Machines, of which the following is a specification.

My improvement relates to machines for washing wool and other similar fibers, and it consists in a new and useful construction and combination of the several parts thereof, substantially as hereinafter described.

In the drawings:—Figure 1 is a top plan view of a wool-washing machine provided with my improvements. Fig. 2 is a longitudinal vertical section thereof on the dotted line $x-x$ of Fig. 1. Fig. 3 is a vertical transverse section thereof on the dotted line $z-z$ of Fig. 2. Figs. 4 and 5 are respectively face and edge views of a chain and sprocket gear construction enlarged from Fig. 2.

My invention relates especially to the mode of operating the rake or carrier, to have it convey the fiber in a more even and direct manner through the bowl and to the squeeze rolls.

A is the bowl of the machine, having a plug or stopper, a , in its bottom for drawing off the washing fluid, and having the perforated false bottom, a^2 , extending through a portion of the bowl horizontally and thence upward, forming an inclined carrier bed with a pitch or incline, a^3 , at the end leading to the squeeze rolls B, B^2 . The rake or harrow 1 carries the fiber through the bowl and partly up the carrier bed, when it is taken by the carrier, 2, and the intermediate carrier, 3, and carried forward and delivered to the squeeze rolls. The intermediate carrier, 3, is pivoted to the rake, 1, by the pivot, 4, and to the carrier 2 by the pivot, 5, so as to form a continuous articulated carrier which, by its movement, can conform quite closely, in progressing forward through the bowl, to the false bottom, a^2 , both over its horizontal and its inclined portion, and the chief object of my invention is to provide such a means of propelling the carrier and suspending it that it shall in its forward movement thus conform to the lines of the false bottom, a^2 , and give the greatest possi-

ble direct movement forward to the fiber at each reciprocation of the carrier.

On the upper side of the carrier, 1, are firmly attached the posts, 6, 7, which at their upper ends are connected by the pivots, 8, 9, to the endless chains, 10, 11, which pass around the sprocket wheels, 12, 13, 14, 15. The sprocket wheels, 12 and 14, are mounted upon horizontal studs projecting from the pipe boxes, 16, 18, while the sprocket wheels 13, 15, are mounted upon shafts, 20, 21, which pass through the pipe boxes 17 and 19, and carry pulleys on their outer ends preferably driven by chains, for revolving the sprocket wheels. It will be observed that the sprocket wheels, 13, 15, being driven will themselves drive the sprocket wheels, 12, 14, by the same chains, 10, 11, which carry the harrow, 1, and that by the revolution of these sprocket wheels and chains I am enabled to obtain a horizontal movement of the harrow parallel with the bottom, a^2 , of the bowl and more nearly conforming to it than by any system of cranks, used to carry the harrow in place of the chains.

In order to carry the carrier, 2, and cause it to conform to the carrier bed portion of the bottom, a^2 , I suspend it by links, 22, 23, to the endless chains, 24, 25; these links being pivoted, however, to the carrier, 2, at their lower ends as well as to the chains at their upper ends, in order to allow for the necessary yielding to enable the carrier to conform to the movement of the rake 1. The chain 24 passes around the sprocket wheels, 26, 27, which are suspended in position by the pipe boxes 28, 29. These pipe boxes are made shorter than the adjacent ones, 18, 19, in order to allow the sprocket wheel, 26, to lap by the sprocket wheel, 15, so that the upper pivot of the link, 22, and the link may pass around behind the wheel, 15, without interfering with it, and the chain, 24, with its sprocket wheels is inclined upward so that its parallel portions shall also be parallel with the inclined part of the bottom, a^2 , of the bowl. The sprocket wheel 26 is supported upon the stud, 26^a, which projects from the pipe box, 19, and the sprocket wheel 27 is supported upon and revolves with the shaft, 27^a, which projects beyond the frame, to allow

it to be driven as hereinafter described. The chain, 25, is supported and carried by the sprocket wheels, 30, 31, which are supported by the pipe boxes, 32, 33; the sprocket wheel 30 revolving on a stud projecting from the pipe box, 32, and the sprocket wheel 31 revolving on the shaft, 34, which passes through the pipe box, 33, and projects outside of the frame for the purpose of driving the same as hereinafter described.

In order to relieve the chains and sprocket wheels from a large portion of the strain of carrying the rake, 1, and carriers 2 and 3, I have adopted an improvement upon the mechanism shown in the British patent granted to Holden and Holden September 6, 1876, No. 3,509, as follows: In the face of the posts 6, 7, I affix two studs 35, 36, projecting outward, and to these I attach cords, 37, 38, which pass over pulleys, 39, 40, which are mounted on the rods, 41, 42; the latter being supported by the framework, F, F, of the machine at each end. To the other ends of these cords I attach weights, 43, 44, which are so constructed as to counterbalance the weight of the harrow, 1, or perhaps a trifle more. On top of the carrier, 2, I attach the eye, 45, and to this attach the cord, 46, which passes over the pulley, 47, similarly sustained on the rod, 48, and has the weight, 49, attached to the other end of the cord and arranged to counterbalance the weight of the carrier, 2. By this arrangement the strain of lifting the carrier upward is largely taken from the chain and sprocket wheels, and the carrier is suspended and always counterbalanced evenly and equally by the weights, in whatever position it may be, which is not the case where such weights are carried on the ends of levers, or other similar connections, to counterbalance the carrier.

The various chains and sprocket wheels for carrying the rake are driven as follows: Upon the shaft, b, of the upper squeeze roll, 45, B, is attached at one end the pulley, 50, and at the other end the pulleys, 51, 52. The pulley 52 is to be driven from any suitable counter-shaft. The pulley 50 is belted to the pulley, 53, on the end of the shaft, 34. The pulley 51 is belted to the pulley, 54, on the shaft 27^a. Another pulley, 55, on this same shaft is belted to pulley, 56, on shaft 21. Another pulley, 57, on the same shaft is belted to pulley, 58, on shaft 20. These beltings are preferably in the form of chains and sprocket gears, to keep the parts working accurately in unison.

The double articulation of the harrow, 1, carrier, 2, and intermediate carrier, 3, enables the harrow 1 to traverse around the larger sprocket wheels without materially interfering with the operation of the carrier, 2, which traverses around the smaller sprocket wheels.

It will be observed that the driving pulleys 50 and 53, 51 and 54, and 55, 56, 57, and 58, are made in proportion to the size of the

sprocket wheels which they drive; that is to say, as the chain which passes around the sprocket wheels, 14, 15, although it carries the harrow, 1, the same horizontal distance 70 as the chain which passes around the sprocket wheels, 26, 27, also lifts the harrow higher than the carrier, 2, is lifted, the chain, 11, must therefore be longer than the chain 24, hence the pulleys 55, 56, which drive the chain, 75 11, must be as much larger as that chain is longer, in order that the harrow, 1, may be brought around to the point where it is shown in Fig. 2 at the same instant of time that the carrier, 2, is brought around to the position 80 shown. This difference in size of the driving pulleys in proportion to the sprocket wheels can be readily calculated by the mechanic who constructs the machine, and it must be allowed for with the sprocket wheels, 85 30, 31, in the same manner.

What I claim as new and of my invention is—

1. In combination with the harrow 1, the supporting chains 10, 11, and the sprocket 90 wheels carrying the same, disposed so that the parallel portions of said chains are parallel to the line of forward movement desired for the harrow through the bowl, substantially as described. 95

2. The combination of the harrow 1, the supporting chains 10, 11, their supporting sprocket wheels arranged to drive the harrow through the bowl reciprocally, and one or more counterbalancing weights attached to the harrow 100 by means of cords passing over pulleys, and arranged to relieve the chains and sprocket wheels from the weight of the harrow, substantially as described.

3. The combination of the harrow 1, supported upon chains and sprocket wheels, with the carrier, 2, linked thereto, and also supported upon chains and sprocket wheels, by swinging links, arranged to convey the wool up the carrier bed as the harrow moves 110 through the bowl, substantially as described.

4. The combination, in a wool-washing machine, of a carrier or harrow formed of two portions linked together, one portion carried by chains and sprocket gears arranged at one 115 angle, and the other portion carried by chains and sprocket gears arranged at another angle to the surface of the fluid in the bowl, substantially as described.

5. The combination, in a fiber-washing machine, of three harrows or carriers, 1, 2, 3, articulated or linked together, and driving mechanism arranged to propel one of these carriers forward at one angle or inclination to the surface of the washing fluid in the 125 bowl, and the others at a different forward inclination or angle to said fluid surface, simultaneously, substantially as described.

6. The combination, in a fiber-washing machine, of three harrows or carriers, 1, 2, 3, articulated or linked together, driving mechanism arranged to propel one of these carriers 130

forward at one angle or inclination to the surface of the washing fluid in the bowl, and the others at a different forward inclination or angle to said fluid surface, simultaneously, 5 and counterbalancing mechanism attached to said harrows or carriers and arranged to suspend the same during their movements, substantially as described.

7. The combination, in a fiber-washing machine, of two harrows or carriers, one driven by chains and sprocket gears of one length or diameter, and the other driven by chains and sprocket gears of a different length and diameter, and driving pulleys connected 15 therewith arranged to cause said harrows to perform their reciprocal movements respect-

ively in the same period of time, substantially as described.

8. The combination, in a fiber-washing machine, of a harrow or carrier sustained and carried by two chains and two pairs of sprocket gears of different lengths and diameters respectively, and provided with driving mechanism arranged to cause each of said chains to complete its movement around the sprocket 25 gears in the same period of time, substantially as described.
